CLAIM

The ornamental design for a wireless charging device, as shown and described in FIGS. 1 through 8.

DESCRIPTION

FIG. 1 is a front view of an example of a wireless charging device, in accordance with embodiments;

FIG. 2 is a rear view of the wireless charging device of FIG. 1;

FIG. 3 is a side view of the wireless charging device of FIG. 1;

FIG. 4 is a side view of the wireless charging device of FIG. 1;

FIG. 5 is a top view of the wireless charging device of FIG. 1; FIG. 6 is a bottom view of the wireless charging device of FIG. 1;

FIG. 7 is a front, perspective view of the wireless charging device of FIGS. 1; and,

FIG. 8 is a rear, perspective view of the wireless charging device of FIG. 1.

Broken lines of the FIGURES are illustrative and depict environment; therefore, they form no part of the claimed design. Additionally, in some embodiments, non-oblique line shading is meant to show contour of represented surfaces, not surface ornamentation.
